SASH FASTENER

Clarence W. Jorgensen, Chicago, Ill., assignor to
Superior Fastener Corporation, Chicago, Ill., a
corporation of Illinois

Application January 15, 1938, Serial No. 185,107

7 Claims. (Cl. 292—202)

This invention relates to a yielding clamp and, more particularly, to a clamp adapted to hold storm sashes, screen sashes and the like in place.

An object of the invention is to provide a sash clamp which is essentially simple, efficient and inexpensive.

A further object of the invention is to provide a sash clamp capable of being readily manufactured at low cost, efficient for its purpose and adapted to be readily used without marring the frame member upon which it is mounted or the sash member which it engages.

The clamp disclosed herein has been designed to be made with a minimum loss of waste material. It is preferably stamped out of resilient sheet metal. The device is so constructed that it may be easily secured in place and operated from year to year as sashes and screens are removed or replaced, the design thereof not detracting from the appearance of the window or door frame or scratching or otherwise marring the finish when swung into and out of engaging position with the sash.

A still further object of the invention is to provide a sash clamp that will securely hold a sash in place, make a tight connection with the window frame, and be self-adjustable to permit use with sashes of different thickness.

It is also an object of the invention to provide a novel type of sash fastener that will readily operate from the interior of the sash to lock the same closed, thereby defeating any unlawful attempt to remove the sash or open the same if hinged to gain access to the window for the purpose of unlawful entry into the building.

Further objects and advantages of the invention will be apparent from the following detailed specification when taken in connection with the accompanying drawings which form a part hereof.

In the drawings:

Figure 1 is a perspective view illustrating a fastener embodying the present invention where the storm or screen sash is of greater thickness than the frame or casing;

Fig. 2 is a similar view illustrating a fastener embodying the present invention where the storm or screen sash is of less thickness than the frame or casing;

Fig. 3 is a sectional view of the screen or window sash and the adjacent frame or casing looking edgewise at the fastener illustrated in Figs. 1 and 2;

Fig. 4 is an enlarged side view of this fastener;

Fig. 5 is a top plan view of this fastener;

Fig. 6 is a sectional view taken on line 6—6 of Fig. 5 to illustrate in cross section the tip of the resilient finger of the fastener;

Fig. 7 illustrates a substantially semi-circular blank out of which the aforesaid fastener is formed;

Figs. 8 to 11, inclusive, illustrate variant embodiments to show how the essential characteristics of the invention may be employed in different forms;

Fig. 12 is a perspective view of a window frame and a storm or screen sash being inserted therein with a novel type of fastener employed to hold the sash in position at the top thereof;

Fig. 13 is a front elevation of the structure shown in Fig. 12;

Fig. 14 is an enlarged face view of the novel type of fastener shown in Figs. 12 and 13;

Fig. 15 is a side view of the fastener shown in Fig. 14;

Fig. 16 is a cross sectional view of a window frame with a storm or screen sash inserted, illustrating a novel type of fastener that interiorly locks said sash closed;

Fig. 17 illustrates in perspective the manner in which the members of the fastener, shown in Fig. 16, cooperate; and,

Fig. 18 is an enlarged detail view of this latter type of fastener.

It will be mentioned at the outset that the preferred form of fastener embodying the invention is preferably a metal stamping formed out of a substantially semi-circular blank. However, certain essential features of the invention may be incorporated in fasteners that may be differently formed and not necessarily of the shape of the preferred embodiment.

The preferred form of fastener illustrated in Figs. 1 to 7, inclusive, is constructed or stamped out of metal of substantially semi-circular shape, as shown in Fig. 7. This fastener, designated A, comprises a base portion 1 formed along the base edge 2 of blank 3 shown in Fig. 7. In the forming operation, blank 3 may be cut along line 4 to form a resilient finger 5 that is coextensive with said base portion at one end, whereby the material 6 at the center of the blank may be bent upwardly to provide an upstanding ear 7 capable of being manually gripped to rotate the fastener about its mounting. Base portion 1 is depressed at 8 and perforated at 9 to receive a securing screw 10. Depressing a portion of base 1 about perforation 9 advantageously furnishes a recess in which the head of securing screw may lie, and at the same time provide a limited bearing surface 55.

between the base portion 1 and the sash frame or casing upon which the device is mounted. Providing a limited bearing surface in this manner allows the fastener to be easily rotated about securing screw 10 to overcome sticking and prevent marring of the finish of the frame or casing.

5 Finger 5 is slightly offset upwardly at 11 with respect to base portion 1, being curved downwardly again at 12 to bring its tip 13 below the plane of base portion 1.

10 Storm and screen sashes are made in standard stock sizes but they vary at times in thickness. Recesses in window and door frames adapted to receive storm and screen sashes will also invariably differ in dimension according to the design and construction of the building. Sash fasteners must, therefore, be capable of firmly engaging and holding the sashes in such recesses, notwithstanding these differences in dimension 15 between the depth of the recess and the thickness of the sash.

15 Figs. 1 and 2 illustrate how the present fastener advantageously overcomes the said differences in dimension between the frame recess and the sash. Finger 5 is provided with an inherent resiliency by virtue of its curved formation that causes its tip 13 firmly to bear against the sash whether it lies within the frame or casing recess, as shown in Figs. 2 and 3, or extends beyond the frame or casing recess, as shown in Fig. 1. When fastener A is rotated about securing screw 10 by gripping upstanding ear 7 and turning the fastener, tip 13 of finger 5 will readily flex upwardly and over the edge 15 of the sash 16 if the latter extends beyond the frame or casing 17. To provide a smooth surface that in effect will give a cam-like action to tip 13 of finger 5 when it is forced to ride over a protruding sash edge, like that of 15 in Fig. 1, 20 this tip 13 is bent upwardly at 18 and the side edges 19 and 20, as well as the leading edge 21 thereof, are turned over, this being illustrated in detail by the cross section shown in Fig. 6 and taken along line 6-6 in Fig. 5 through tip 30 13. Hence, the leading ledge 21 on tip 13 will not catch or dig into or otherwise mar edge 15 of sash 16 but will ride thereover to bring this tip 13 of finger 5 over and upon the surface of sash 16 to firmly bear thereagainst and hold 35 this sash tightly in position against frame 17.

40 Fastener A may be secured upon frame 17 at different distances from the sash opening edge. I have illustrated in Figs. 1 and 2 a portion of base 1 also riding over edge 15 and bearing against sash 16, if so desired. To prevent edge 2 of base 45 15 of sash 16, an upstanding lip 17 may be formed therealong.

45 If sash 16 is of less thickness than the depth of the frame or casing recess, as illustrated in Fig. 2, finger 5 will cause its tip 13 to readily engage and bear against the sash to hold it firmly in position. It will be noted that fastener A may be formed out of a substantially semi-circular blank, as pointed out above, without incurring any waste material, and consequently, when it is formed out of a continuous strip the waste material between successive fasteners will be reduced to a minimum. Finger 5 is given an 50 inherent resiliency by virtue of its formation that causes its tip to exert sufficient pressure against the sash it engages whereby such sash is firmly held in position. Fastener A may be easily operated and readily mounted on the frame without detracting from the appearance of the window 55 opening. Its operation will not mar or scratch the finish of the frame or sash.

60 The variant embodiments B, C, D and E, illustrated in Figs. 8 to 11, inclusive, incorporate certain essential features considered to be within the scope of the invention. The fastener B shown in Fig. 8 includes a base 22 that is perforated to receive a securing screw 23 for mounting the fastener, a resilient finger 24 and an upturned ear 25 adapted to be manually gripped to 65 swing this fastener about securing screw 23 whereby the resilient tip of finger 24 may be moved over and upon member 26 to bear resiliently thereagainst in order to hold it in position. Upturned ear 25 lies between base 22 and finger 24. The structure C, illustrated in Fig. 9, is substantially the same as illustrated in Fig. 8 except that base 27 is disposed substantially closer to resilient finger 28 and this resilient finger is adapted to have its tip bent at right angles 70 so as to lie parallel to the edge of the member 29 which it holds in position. The fastener D illustrated in Fig. 10 is substantially the same as the preferred embodiment illustrated in Figs. 1 to 7, inclusive. Instead of upturned ear 7 in 75 the preferred embodiment being formed along the inner edge 29 of the base, the outer edge is formed to provide this upturned ear 7. Fastener E, shown in Fig. 11, has its resilient finger 30, base portion 33 and upturned ear 34 arranged 80 in slightly different relation, but these component parts are so associated with each other in a fastener structure of this type as to accomplish substantially the same results as illustrated in the previous embodiments. Resilient finger 35 30 is somewhat curved to bring its tip 31 practically parallel to the edge of the member 32 which it holds in position while base 33 is formed at the opposite end of this finger with upturned ear 34 along the edge of base 33.

85 Frequently, fasteners of the type heretofore described cannot be conveniently used along the top rail of the window frame or casing. In Figs. 14 and 15, a fastener 35 is illustrated that is simple and formed of a rectangular piece of metal, and is so shaped as to have base 36 perforated at 37 for a securing element, and a resilient finger 38 of V-shape that is so bent that the apex 39 of the V may bear against the sash to hold it in position. To illustrate, Fig. 12 shows two fasteners 36 mounted upon the upper rail of a window frame or casing. Resilient finger 38 is allowed to protrude below the lower edge of this upper rail. The sash is moved upwardly in position so that the upper edge thereof will be moved under the outer leg 40 of finger 38. Leg 40 is bent outwardly to allow the upper edge of the sash to be moved into position within the frame without any interference whereby the finger 38 will securely hold the sash in position.

90 In order to lock the sash interiorly to prevent unauthorized access to the window by removing the sash on the outside of the building, a slotted bracket 45 may be attached at any suitable location within the window frame, the member 46 shown in Fig. 17 representing, for example, the usual stop strip of a window frame. Bracket 45 may have its legs 47 and 48 of such angular relation as may be necessary in view of the manner in which the bracket must be mounted in order to properly position leg 47 having slot 49 therein. A second bracket 51 provided in the form of a strap having a central offset portion 52 may be attached to the inside of sash member 53. Offset portion 52 is perforated to re- 95

ceive a bolt 54. The head of bolt 54 lies within the recess provided by offset 52 whereby the bolt will be held in position and is not free to drop out of place when bracket 51 is attached against a sash member. Bracket 51 is so located upon sash member 53 that when this sash member is brought to closed position against stop 46, the shank of bolt 54 may be dropped into slot 49. Slot 49 is slightly cut away at 50 so that after bolt 54 is moved transversely into slot 49, it may be raised slightly to move into the cut-away portion 50. A nut 55 may then be used to lock bolt 54 in this position.

Hence, there is disclosed in the present invention a complete set of storm or screen sash fasteners for mounting, securing and locking the sash members in proper position within a window or door frame.

Without further elaboration, the foregoing will so fully explain the gist of my invention that others may, by applying current knowledge, readily adopt the same for use under varying conditions of service, without eliminating certain features, which may properly be said to constitute the essential items of novelty involved, which items are intended to be defined and secured to me by the following claims.

I claim:

1. A storm sash fastener formed as a sheet metal stamping out of a blank substantially of semi-circular shape comprising a base portion having a perforation for a securing screw, a curved resilient finger and a manually engageable lug formed along one edge of said base, said finger extending about said lug and having its tip normally lying below said base portion.

2. A storm sash fastener adapted to be secured to a sash frame to resiliently bear against a storm sash comprising a stamping having a base portion provided with a perforation for a securing screw, an upturned ear on said base portion adapted to be gripped to rotate the latter about said securing screw, and a resiliently formed finger on said base portion extending therefrom in curved formation, the tip of said finger being slightly upturned and having its edges turned-over to present a substantially smooth cam-like surface at the leading edge of said finger tip as it is swung over and upon the storm sash to resiliently bear thereagainst.

3. A storm sash fastener adapted to be secured to a sash frame for resiliently bearing against a storm sash comprising a base portion having a perforation for a securing screw, and a resiliently formed finger extending forwardly from along one edge of said base portion, said finger being curved to bring its tip over and upon the storm sash when said base portion is rotated

about said securing screw, said tip having its forward and side edges turned over to present a substantially smooth cam-like surface for said tip as it is swung over and upon the storm sash to resiliently bear thereagainst.

4. A storm sash fastener adapted to be secured to a sash frame for resiliently bearing against a storm sash comprising a base portion adapted to be rotatably secured to the sash frame, and a resiliently formed finger extending forwardly from alone one edge of said base portion, said finger being curved to bring its tip over and upon the storm sash when said base portion is rotated, a substantial portion of said finger being curved to lie above the plane of said base portion, the tip of said finger being curved to lie below the plane of said base portion.

5. A storm sash fastener adapted to be secured to a sash frame for resiliently bearing against a storm sash comprising a metal stamping formed out of a substantially semi-circular blank having a base portion formed along the straight edge of said semi-circular blank, said base portion being attached to the sash frame for rotatable movement, a finger formed along the curved edge of said semi-circular blank and having its tip so bent as to resiliently bear against the sash when said base portion is rotated, and an upstanding manually engageable ear for rotating said base portion, said ear comprising the central portion of said semi-circular blank.

6. A sash fastener formed out of a blank of substantially semi-circular shape comprising a base provided along the straight edge of said semicircular blank, a finger provided along the curved edge of said semicircular blank, said finger being resilient and adapted to bear against the sash member to be held when said base portion is moved, and an upstanding manually engageable ear for moving said base portion, said ear comprising the central portion of said semi-circular blank lying between said base portion and said finger.

7. A sash fastener adapted to be secured to a sash frame for resiliently bearing against a sash member comprising a base portion of substantially elongated formation, a resilient finger extending outwardly from along one of the side edges at one end of the base portion and around said base portion to lie substantially in close proximity to the opposite end of said base portion, both the tip of said finger and said opposite end of the base portion being adapted to engage and hold the sash member within the sash frame to which said base portion may be secured, and a manually engageable upstanding ear on said base portion.

CLARENCE W. JORGENSEN.

CERTIFICATE OF CORRECTION.

Patent No. 2,184,674.

December 26, 1939.

CLARENCE W. JORGENSEN.

It is hereby certified that error appears in the printed specification of the above numbered patent requiring correction as follows: Page 1, second column, line 33, for "susbtantly" read substantially; page 3, second column, line 11, claim 4, for the word "alone" read along; and that the said Letters Patent should be read with this correction therein that the same may conform to the record of the case in the Patent Office.

Signed and sealed this 19th day of March, A. D. 1940.
